UNITED STATES PATENT OFFICE.

JACOB FISHER, OF LAMBERTVILLE, NEW JERSEY, ASSIGNOR TO LAMBERTVILLE RUBBER COMPANY, OF LAMBERTVILLE, NEW JERSEY, A CORPORATION OF NEW JERSEY.

DESIGN FOR A RUBBER BALL.

No. 38,616.

Specification for Design.

Patented June 11, 1907.

Application filed December 20, 1906. Serial No. 348,827. Term of patent 7 years.

To all whom it may concern:

Be it known that I, JACOB FISHER, a citizen of the United States, residing at Lambertville, in the county of Hunterdon, State of New Jersey, have invented a new, original, and ornamental Design for Rubber Balls, of which the following is a specification, reference being had to the accompanying drawing, in which the figure is a perspective view showing my new design.

I claim—
The ornamental design for a rubber ball, as shown.

JACOB FISHER.
